UNITED STATES PATENT OFFICE.

TERRIENCE LORENCE MCKENNA, OF LINDON, COLORADO.

RESILIENT WHEEL.

1,313,707.

Specification of Letters Patent.

Patented Aug. 19, 1919.

Application filed March 12, 1919. Serial No. 282,177.

To all whom it may concern:

Be it known that I, TERRIENCE LORENCE MCKENNA, citizen of the United States, residing at Lindon, in the county of Washington and State of Colorado, have invented certain new and useful Improvements in Resilient Wheels, of which the following is a specification, reference being had to the accompanying drawings.

10 This invention relates to an improved resilient wheel, particularly adapted for use in connection with automobiles. As one of the objects of the invention, it is the aim to provide simple, efficient and practical means 15 of connection between the hub and the rim of the wheel.

The invention further aims to provide resilient means for the spokes, mounted upon the hub, and also to provide means for connecting the resilient means to the hub.

20 The invention further aims to provide means to prevent creeping of the resilient means with relation to the hub.

The invention further aims to provide improved connections between the spokes of the wheel and the rim, said connections being of such character as to permit the spokes to coöperate with the resilient means, to insure resiliency for the wheel.

30 While the design and construction at present illustrated and set forth is deemed preferable, it is obvious that as a result of a reduction of the invention to a more practical form for commercial purposes, the invention 35 may be susceptible of changes, and the right to these changes is claimed, provided they are comprehended within the scope of what is claimed.

The invention comprises further features 40 and combination of parts as will be herein-after set forth, shown in the drawings and claimed.

In the drawings:

Figure 1 is a view in side elevation and 45 partly in section of the improved resilient wheel constructed in accordance with the invention.

Fig. 2 is a sectional view on line 2—2 of Fig. 1, more clearly showing the mounting 50 of the resilient means of the hub, and illustrating the hub as being constructed in two sections.

Fig. 3 is an enlarged detail view in perspective of a portion of the hub and the

resilient means, and the connection between 55 the resilient means and the hub.

Referring more especially to the drawings 1 and 2 designate the two sections of the hub, which are interconnected as shown at 3, there being bolts 4 penetrating the two sections 60 for fastening them together.

The two sections of the hub are provided with annular recesses 5 angular in cross-section, which, when the two sections are connected, form a channel. The bottom of 65 the channel constitutes a seat for a plurality of coil springs 6, there being a circular rod or bolt 7 passing through the coils to anchor them in the channel. The adjacent ends of the rod or bolt are connected by a suitable 70 turn buckle 8. By means of the buckle or rod the bolt may be securely tightened, whereby the springs may be fastened in place firmly.

The flanges 9 and 10 of the hub sections 75 are provided with radial slots 11 and 12. It is to be noted that the slots 11 of one of the flanges are in staggered relations with the slots 12 of the opposite flange. The end portions of each coil spring are extended 80 laterally, constituting arms 13, the outer end parts of which are turned to form coils 14. The extremities 15 beyond the coils 14 are fastened in any suitable manner into the inner ends of the spokes 16 of the wheel. 85 These spokes may be constructed of any suitable material preferably wood, and their inner parts have surrounding steel sleeves 17, to reinforce the spokes, and to prevent them from splitting, incident to the strain of 90 the arms in the spokes. It is to be noted that the notches in the flanges are arranged in staggered relations, for the accommodation 95 of the spring arms which project laterally from the coil springs, which are mounted in the channel of the hub. In other words, since the spring arms extend laterally from the opposite ends of each coil spring it is necessary to arrange the notches in staggered relations, and since the arms are capable of yielding owing to the construction and arrangement of the coil spring, it is obvious 100 that the notches act to guide the coil springs in their movements, and also to prevent creeping of the coil springs relative to the 105 circular bolt or rod. Obviously this is accomplished owing to the arms contacting with the walls of the notches. The adjacent

faces of the flanges of the hub are provided with annular shoulders 18, to be engaged by a retaining band 19. This band overflies the coil springs and prevents radial displacement of the springs.

The wheel is provided with the usual rim 20 having a channel 21, to be engaged by a conventional form of solid rubber tire 22. Carried by the inner face of the rim are 10 spring steel plates 23, which are secured to the rim as shown at 24. These plates are V-shaped, and have openings 25, through which the spokes movably pass. The ends of the spokes are provided with reduced portions 26 and adjoining shoulders 27. The inner face of the rim has secured thereto flanged members 27, into which the coil springs 28 extend and engage. These coil springs in turn receive the reduced portions 20 of the outer ends of the spokes, said springs contacting with the shoulders, thereby insuring additional resiliency for the wheel.

The invention having been set forth, what is claimed as new and useful is:

25 1. In a resilient wheel, the combination with a hub member provided with a channel, of a plurality of coil springs secured in the channel concentrically with the hub, said springs having laterally extending spring 30 arms, a rim, and spokes connecting the rim and the spring arms.

35 2. In a resilient wheel, the combination with a hub member provided with a channel, of a plurality of coil springs secured in the channel concentrically with the hub, said springs having laterally extending spring arms, a rim, and spokes connecting the rim and the spring arms, and means carried by 40 the hub member receiving and co-operating with the spring arms to prevent creeping of the coil springs in the channel.

45 3. The combination with a hub member provided with a channel, of resilient means seated and secured in the channel concentrically with the hub, means engaging the walls of the channel and overlying the resilient means to additionally prevent radial displacement of the resilient means, said resilient means having laterally extending 50 spring arms terminating in radial parts, a

a rim and spokes connecting the radial parts and the rim.

4. The combination with a hub member provided with a channel, of resilient means seated and secured in the channel concentrically with the hub, means engaging the walls of the channel and overlying the resilient means to additionally prevent radial displacement of the resilient means, said resilient means having laterally extending 55 spring arms terminating in radial parts, a rim, spokes connected to the radial parts, and yieldable means connecting the outer ends of the spokes and the rim.

5. The combination with a hub member 65 provided with a channel, of resilient means seated and secured in the channel concentrically with the hub, means engaging the walls of the channel and overlying the resilient means to additionally prevent radial 70 displacement of the resilient means, said resilient means having laterally extending spring arms terminating in radial parts, a rim, and spokes connecting the radial parts and the rim, said hub having means in staggered relations to receive and guide said spring arms and to prevent creeping of the 75 resilient means relative to the hub.

6. The combination with a hub member provided with a channel, of resilient means 80 seated and secured in the channel concentrically with the hub, means engaging the walls of the channel and overlying the resilient means to additionally prevent radial displacement of the resilient means, said resilient means having laterally extending 85 spring arms terminating in radial parts, a rim, spokes connected to the radial parts, and yieldable means connecting the outer ends of the spokes and the rim, said hub 90 having means in staggered relation to receive and guide said spring arms and to prevent creeping of the resilient means relative to the hub.

In testimony whereof I hereunto affix my 95 signature in the presence of two witnesses.

TERRENCE LORENCE MCKENNA.
